(57) **CLAIM**

The ornamental design for a toilet plunger storage device, as shown and described.

DESCRIPTION

FIG. 1 is a perspective view of a toilet plunger storage device according to the invention;

FIG. 2 is a perspective view similar to FIG. 1 showing a cover separated from a receptacle;

FIG. 3 is a side elevation view of the device of FIG. 1;

FIG. 4 is a top plan view of the device of FIG. 1;

FIG. 5 is a bottom plan view of the device of FIG. 1;

FIG. 6 is a side elevation view of the device of FIG. 1 taken from the side opposite to that shown in FIG. 3; and,

FIG. 7 is a side elevation view of the device of FIG. 1 taken from the right in FIG. 3.
